UNITED STATES PATENT OFFICE.

FLOREN CIPAR, OF CHICAGO, ILLINOIS.

DRUM.

No. 881,109.

Specification of Letters Patent. Patented March 10, 1908.

Application filed May 15, 1907. Serial No. 373,765.

To all whom it may concern:

Be it known that I, FLOREN CIPAR, a resident of Chicago, in the county of Cook and State of Illinois, have invented certain new and useful Improvements in Drums, of which the following is a full, clear, and exact description.

The invention relates to musical instruments and more particularly to drums.

10 One object of the invention is to provide an improved construction for a drum which is foldable and which permits the drum-heads to be brought together into close proximity for convenience in carrying and which 15 comprises a collapsible body which may be extended and secured in extended position when the instrument is to be used. This feature is particularly desirable in the larger sizes of drums, such as are commonly known 20 as "bass-drums".

The invention further designs to provide a drum of improved construction.

25 The invention consists in the several novel features hereinafter set forth and more particularly defined by claim at the conclusion hereof.

In the drawings: Figure 1 is a perspective of a drum embodying the invention. Fig. 2 is a section showing the parts in position as 30 sumed when folded together for convenience in transportation. Fig. 3 is a section, the drum-heads being shown in operative relation and the body in extended position. Fig. 4 is a detail showing the adjusting-device for 35 one of the drum-heads.

The instrument comprises a pair of drum-heads 12 each secured to a flesh-hoop 13 over which fits a retaining-hoop 14 adapted to hold the flesh-hoop in desired position 40 to maintain the drum-head under tension. Adjacent each drum-head and within the flesh-hoop is a body-retaining band or section 15 over which the drum-head is extended and around which the flesh-hoop and retaining-hoop are disposed. Straining-devices 45 in desired number for each drum-head and whereby they are held and adjusted comprise lugs or brackets 16 which are secured to body-bands 15 by screws 17, hooks 18 50 adapted to engage the retaining-hoops and screws 19 for adjusting the hooks to tighten or loosen the retaining-hoops and flesh-hoops to correspondingly adjust the drum-heads.

55 The body 11 of the drum is formed of

suitable flexible material, such as sheep-skin, which is adapted when adjusted to form a body of the proper shape between the drum-heads. Each of the ends of said body is secured to one of the body-bands 15 by 60 an inner loop 20 and screws 21. The primary purpose of providing the body of flexible material is to permit the body to collapse so the drum-heads may be brought in close or compact relation as seen in Fig. 2 for 65 convenience in carriage or transportation. Body-bands 15 provide means connected to the body whereto the drum-heads may be attached and body-sections which may be brought into close relation while retaining 70 the proper relation between the ends of the body and the drum-heads. For the purpose of securing the body in extended and operative position, separating devices or spreaders which are independent of the straining- 75 devices for the drum-heads are provided.

Each spreader comprises a pair of lugs or brackets 23 respectively secured to the body-bands by screws 24 and having openings therein which are adapted to receive the opposite ends of rods 25. The outer end of each bracket 23 is provided with a thumb-screw 26 adapted to impinge against one end of the rod 25 to hold the body taut and to hold the body and drum-heads carried thereby in extended or operative position. By adjusting screws 26, the desired tension may be put on the flexible body. To permit the flexible body to be folded inwardly between the drum-heads, it is provided with a number 80 of eye-lets 28 having openings therein for ingress and egress of air during the folding operation.

The invention possesses several important advantages. In practice it has been found that 95 the collapsible body when put under tension or held taut has as good sound producing properties as a rigid body and also permits the body to collapse so the drum-heads can be brought into closed or compact relation 100 for convenience in carrying. This advantage is of particular moment in the use of large bass drums. The construction of the collapsible body is such that the drum-heads may be independently adjusted as desired. 105

The invention is not to be understood as restricted to the particular construction set forth and described but may be modified without departing from the spirit and scope of the invention.

Having thus described the invention, what I claim as new and desire to secure by Letters Patent, is:

- 5 1. In a musical instrument, the combination of a pair of drum-heads, and a collapsible body of flexible material therebetween.
- 10 2. In a musical instrument, the combination of a pair of drum-heads, and a collapsible body of flexible material therebetween and having air openings therein.
- 15 3. In a musical instrument, the combination of a pair of drum-heads, a body-band for each of said heads, and a body of flexible material connecting said bands.
- 20 4. In a musical instrument, the combination of a body of flexible material, drum-heads respectively connected to said body, and means for securing said bands so the flexible body will be held taut.
- 25 5. In a musical instrument, the combination of a pair of body-bands, a body of flexible material between said bands, drum-heads respectively connected to said bands, and means for securing said bands so the flexible body will be held taut.
- 30 6. In a musical instrument, the combination of an extensible body, means for stretching said body, and drum-heads respectively connected to said body.
- 35 7. In a musical instrument, the combination of a body, of flexible material, a band

at each end of the body, means for holding the bands apart to stretch the body, and drum-heads connected to the bands.

8. In a musical instrument, the combination of a flexible body, means for stretching said body, and drum-heads respectively connected to said body.

9. In a musical instrument, the combination of a pair of body-bands, a body of flexible material between said bands, and drum-heads adjustably connected to said bands.

10. In a musical instrument, the combination of a pair of body-bands, a body of flexible material between said bands, spreaders for said body, and drum-heads adjustably connected to said bands.

11. In a musical instrument, the combination of a body of flexible material, a body-retaining-band at each end of said body, spreader-devices between said bands, and drum-heads connected to said bands.

12. In a musical instrument, the combination of a body of flexible material, a body retaining-band at each end of said body, spreading-devices between said bands, drum-heads connected to said bands, and straining-devices between said drum-heads and said bands.

FLOREN CIPAR.
